UNITED STATES PATENT OFFICE.

WILLIAM G. KROUSE, OF WYOMING, IOWA.

ENGINE-SUPPORTING DEVICE.

1,225,651.

Specification of Letters Patent.

Patented May 8, 1917.

Application filed April 3, 1916. Serial No. 88,533.

To all whom it may concern:

Be it known that I, WILLIAM G. KROUSE, a citizen of the United States, residing at Wyoming, in the county of Jones and State 5 of Iowa, have invented certain new and useful Improvements in Engine-Supporting Devices, of which the following is a specification.

The present invention relates to supports 10 and more particularly to new and useful improvements in engine handling and supporting devices.

The primary object of my invention is to provide in a simple and compact structure 15 an improved engine support having a main base frame, a supporting frame, and an object receiving frame arranged whereby the object may be turned into different positions for inspection and repair.

Another object of my invention is to provide a support of the class described which may be transported from place to place without disassembling the support, the object carrying frame having means associated therewith whereby the object carried therein may be operated, should it be an engine, and at the same time turned into different positions for inspection purposes.

A further object of my invention is to provide a modified form of supporting member for attachment to the first mentioned form of my invention, whereby the object supported may be carried on a rigid base.

A still further object of my invention is to provide a device of the character above described which is simple and light in construction, cheap to manufacture, strong and durable, and effective in operation.

Other objects and advantages to be derived from the use of my invention will appear from the following detail description and the claims, taken with an inspection of the accompanying drawings, in which—

Figure 1 is a side elevation of a support embodying the improvements of the preferred form of my invention.

Fig. 2 is a top plan view of the same.

Fig. 3 is a rear end elevational view of the same.

Fig. 4 is a side elevational view of an attachment for my invention applied thereto,

Fig. 5 is a front end elevation of the same,

Fig. 6 is a perspective view of a further attachment to my invention, showing the same applied,

Fig. 7 is a side elevation of a still further attachment for my invention, showing the same in use,

Fig. 8 is a top plan view of the same,

Fig. 9 is a fragmentary perspective view of the modified form of my invention illustrated in Figs. 7 and 8,

Fig. 10 is a vertical sectional view taken on the line 10—10 of Fig. 1, looking in the direction of the arrows,

Fig. 11 is a fragmental vertical sectional view taken on the line 11—11 of Fig. 10 looking in the direction of the arrows.

Referring more particularly to the drawings, in which similar characters of reference designate like and corresponding parts throughout the various views, 1 and 2 designate the supporting base bars of the stationary frame, said bars being preferably formed from angle iron and having the vertical converging front and rear bars or standards 3 and 4, respectively. The rear standards 4 are preferably formed from a single angle iron bent intermediate its ends as at 5. This formation allows for reception of a trunnion 6 carried by a casting 7 having secured thereto, by means of screws 8, a pair of T-irons 9 and 10. The T-irons 9 and 10 are offset as at 12 to provide object receiving arms 13 and 14. The casting 7 extends laterally from the T-irons 9 and 10 to provide a support, the free end thereof being bifurcated to provide spaced arms 11, for a purpose which will hereinafter appear.

I provide means for swinging the arms 13 and 14 forming the object receiving frame into different angles, said means including a gear wheel 15 having peripheral laterally extending flanges 15' and the conventional teeth. The gear wheel is rotatably mounted in a casing including a pair of semi-circular channeled sections 16 and 17, the inwardly turned flanges 16' and 17' formed on said sections being adapted to embrace the teeth of the gear 15 and snugly engage the flanges 15', whereby to form both a housing and a bearing for the gear wheel. The sections 16 and 17 are mounted on the standards 3 by means of bolts or the like as indicated at 18. I provide means for connecting the T-irons 9 and 10 to said gear wheel, said means including a pair of diametrically oppositely located lugs 18' which are bolted as at 19 to said T-irons. I provide means for rotating the gear 15,

said means comprising a housing 19 cast integrally with the section 17 and having an operating shaft 20 journaled therein carrying a worm 21 for engagement with said gear. A handle 22 is mounted on the free end of the shaft 20 for an obvious purpose. A normally idle shaft 23 is arranged in enlarged openings 24 formed in the gear wheel hub and the bearing trunnion 6, said shaft 10 having an operating handle 26 on the outer free end thereof and a clutch member 27 mounted on the inner free end thereof having a plurality of notches thereon for engagement with the end of a crank shaft of 15 an engine, usually the crank shaft of an internal combustion engine to operate the same when mounted in the supporting frame. A plurality of transverse braces 28 serve to strengthen the angle irons 1 and 2 forming the base frame. The laterally extending flanges of the arms 13 and 14 are provided with openings 29 to which may be attached an engine, the base flange of an internal combustion engine frame resting 20 upon the flanges of the arms 13 and 14.

Referring further to the form of my invention illustrated in Figs. 4 and 5 I have provided an attachment for supporting an engine casing 30 having the usual transmission housing 31 formed thereon, the casing 30 being carried by the engine when in operation in an automobile or the like. In order to support the casing on the carrying frame of my invention I provide a bracket 32 formed of a strip of metal upwardly curved adjacent its end as at 33 and terminating in supporting arms 34 preferably vertical. A pair of flat strips 35 are riveted or otherwise secured to the strip 32 and engaged beneath the lateral flanges of the arms 13 and 14 as best shown in Fig. 5. An outlet for oil and dirt formed by stamping an opening 36 in the strip 32 is provided. The arms 34 are adapted to receive brackets 37 carried by the casing 30. The gear housing 31 of the casing 30 is adapted to seat in the supporting bracket 32 and the free end of the casing 30 is adapted to seat between the arms 11 of the casting 7 as clearly shown in Figs. 4 and 5. Of course, the supporting frame, including the arms 9 and 10, is inverted when used in its capacity as an engine casing support, the casting 7 normally extending downwardly as best shown in Figs. 1-3 and 7 and 8.

In Figs. 7, 8 and 9 I have illustrated a further modified form of supporting member for use in connection with my improved supporting frame, a plurality of clamping members being provided, said clamping members being identical in construction and therefore a description of one will suffice. The clamping members, one of which is shown in perspective in Fig. 9 comprises 65 a strap 40 having slots 41 therein adjacent

the free extremities thereof and a bolt 42, said bolt passing through the strap 40 into a slightly resilient clamping bar 43 which is adapted to engage the arms 13 and 14. A wing nut or the like fastening means 44 is provided on the bolt 42. Laterally adjustable vertical arms 45 are mounted on the strap 40, said arms having bolts 46 in the base portions thereof, said bolts extending through the slots 41 and having adjusting nuts 47 on the lower end. This form of the invention may be used similarly to the form shown in Figs. 4, 5 and 6 serving as a means for stationarily mounting a gasoline engine or similar machine.

Referring to the modified form of my invention illustrated in Fig. 6 it will be noted that I have provided a supporting angle-bar 50 provided with longitudinally extending spaced slots 51 in which are mounted fastening bolts 52 of a pair of bracket members 53 having base portions 54. This arrangement permits longitudinal adjustment of the bracket members for a purpose which will hereinafter appear. The upper free ends of the bracket members 53 are bifurcated to provide divergent spaced arms 55 for a purpose which will hereinafter appear. The angle-bar 50 is arranged transversely of the arms 13 and 14 by means of a clamp including a flat strip 56 engaged beneath the lateral flanges of said arms 13 and 14, a fastening bolt 57 extending through said angle-bar and said flat strip and being adapted to be clamped by means of a nut 58 or the like fastening means. One use of this form of my invention is illustrated in dotted lines in Fig. 6. In this view I have shown in dotted lines an automobile front axle 59 which is arranged on a transverse bar 60 supported by the divergent arms 55 of the bracket 53. Suitable means may be provided for clamping the axle in position and for retaining the bar 60 against longitudinal movement. The opposite end of the axle, as shown, is adapted to be received between the arms 11 of the casting 7. When securely arranged in position the axle is turned at the convenience of the operator.

The uses to which my invention may be put are unlimited in so far as a device of this character is concerned and the attachments which I have hereinbefore set forth are only shown as a few of the ways in which the same may be used. The device may be used as a crane by clamping a carrying arm transversely of the arms 13 and 14 and allowing the same to extend laterally theretrom. By rotating the shaft 20 in the proper direction the arm may be raised consequently lifting an object carried by the outer end thereof. It will therefore, be readily understood that the uses of my invention are many more than those herein-

before set forth and it will be readily appreciated by those skilled in the art that I do not limit myself to the structure shown but reserve the right to make such changes in said structure as do not depart from the spirit and scope of the invention as claimed.

What I claim as new and desire to secure by Letters Patent is:—

1. In a testing frame for internal combustion engines, a base, standards thereon, a supporting frame on said standards, means for rotating the frame including a pair of sections mounted on said standards, a casing formed by said sections, a gear wheel rotatably mounted in the casing, an operating shaft, a worm gear mounted on the end of said shaft meshing with the gear wheel, and the said supporting frame being rigidly connected to the said gear wheel for a purpose specified.
2. In a testing frame for internal combustion engines, a supporting frame, a base, vertically converging front and rear standards, the rear standard being bent intermediate its ends, a casting mounted on the said frame, a trunnion carried by the casting and

engaged in the bent portion of the said rear standard, and spaced arms formed on a laterally extending portion of the said casting for a purpose specified.

3. The combination with an engine supporting device comprising a base, standards thereon, and a pair of T-irons providing a supporting frame, of a bracket including a strip of sheet metal curved adjacent the ends thereof into parallelism with each other to form supporting arms, a pair of strips secured to the said sheet metal strip to engage with the said T-irons for a purpose specified.

4. The combination with an engine supporting device having a base, standards thereon, and a supporting frame, of a gear wheel for rotating said frame, the said gear wheel having an enlarged opening through the hub thereof, a shaft rotatably mounted in said opening, a clutch member mounted on the end of said shaft including, a head having a plurality of notches thereon for a purpose specified.

In testimony whereof I affix my signature hereto.

WILLIAM G. KROUSE.
